UNITED STATES PATENT OFFICE.

SAMUEL J. LEWIS, OF DETROIT, MICHIGAN.

DISPENSING TUBE.

Application filed September 17, 1925. Serial No. 56,885.

This invention relates to improvements in dispensing tubes.

My improvements relate particularly to the cap of dispensing tubes such as are commonly used for tooth paste and the like, the main object of my improvement being to provide an improved dispensing tube which is self-closing, permitting the material being ejected by pressure upon the tube, the tube being effectively sealed or closed when the pressure is released.

Objects relating to details and economies of construction and operation of my invention will definitely appear from the detailed description to follow.

The invention is clearly defined and pointed out in the claims.

A structure which is a preferred embodiment of my invention is clearly illustrated in the accompanying drawing, forming a part of this application, in which:

Fig. 1 is a perspective view of a dispensing tube embodying the features of my invention.

Fig. 2 is a front end view of the cap removed from the tube.

Fig. 3 is a detail view, the cap being in longitudinal section on a line corresponding to line 3—3 of Fig. 2.

Fig. 4 is a detail longitudinal section showing the cap or tip open as when material is being ejected therefrom.

In the drawing similar reference characters refer to similar parts throughout the several views.

Referring to the drawing, the tube 1 is shown conventionally and is of a well known type made of flexible metal having a threaded neck 2.

The cap designated generally by the numeral 3 comprises a base portion 4 of hard rubber and a tip portion 5 of resilient rubber, the tip portion being integrally fixed to the base portion by vulcanizing thereon.

It will be understood that there would be no distinct or uniform line of division between these parts as is indicated by the drawing but it is deemed desirable to thus illustrate the same in the drawing for a better understanding of my improvements.

The walls of the tip portion increase in thickness forwardly to a solid nose portion 6 of substantial length, this nose portion hav-

ing a longitudinal slit 7 cut therein providing a discharge orifice, the resiliency of the material holding this slot normally closed. However, when pressure is applied to the tube, the material is discharged as indicated at 8, the discharge orifice or slot being forced open by the pressure of the material from within. When the pressure is released, the resiliency of the material will close the discharge orifice. The hard rubber portion 4 can be readily threaded to engage the threaded neck.

The tip is preferably flattened as shown as this form is effective in closing and further the material is discharged in a ribbon-like form which is desirable for tooth paste and the like.

I have illustrated and described my improvements in an embodiment which I consider very practical and it is believed that this disclosure will enable those skilled in the art to embody or adapt my improvements as may be desired.

Having thus described my invention, what I claim as new and desire to secure by Letters Patent, is:

1. The combination of a flexible dispensing tube having a threaded neck and a cap comprising a base of hard rubber threaded upon said neck, and a flattened tip of resilient rubber integrally fixed to the base and terminating in a relatively thick wall having a longitudinal slit-like orifice therein normally closed by the resiliency of the material.

2. A cap for dispensing tubes comprising a base of hard rubber, and a flattened tip of resilient rubber integrally fixed to the base and terminating in a relatively thick wall having a longitudinal slit-like orifice therein held normally closed by the resiliency of the material.

3. The combination of a dispensing tube and a cap therefor provided with a chambered tip of resilient material terminating in a tapered relatively thick wall constituting the nose of the tip and having a longitudinal slit therein held normally closed by the resiliency of the material.

In witness whereof I have hereunto set my hand.

SAMUEL J. LEWIS.
